UNITED STATES PATENT OFFICE.

WILLIAM JOSEPF BARING, OF RICHMOND, CALIFORNIA.

DESIGN FOR A TEA OR COFFEE POT.

58,697.

Specification for Design.

Patented Aug. 30, 1921.

Application filed January 21, 1921. Serial No. 439,032. Term of patent 14 years.

To all whom it may concern:

Be it known that I, WILLIAM J. BARING, a citizen of the United States, residing at Richmond, in the county of Contra Costa and State of California, have invented a new, original, and ornamental Design for a Tea or Coffee Pot, of which the following is a specification, reference being had to the accompanying drawing, forming part thereof.

Figure 1 represents a side elevation view of a tea or coffee pot showing my new design; and

Fig. 2 represents a top plan view.

I claim:

The ornamental design for a tea or coffee pot, as shown.

WILLIAM JOSEPF BARING.
